(57) **CLAIM**

The ornamental design for an accessory clip for a smart watch, as shown and described.

DESCRIPTION

FIG. 1 is a top, left side isometric view of our new design for an accessory clip for a smart watch, all other surfaces being the same as the embodiment of FIG. 1 other than the disclaimed surfaces.

FIG. 2 is a left side elevation view of FIG. 1.

FIG. 3 is a right side elevation view of FIG. 1.

FIG. 4 is a top side plan view of FIG. 1.

FIG. 5 is a bottom side plan view of FIG. 1.

FIG. 6 is a front side elevation view of FIG. 1.

FIG. 7 is a back side elevation view of FIG. 1.

FIG. 8 is an isometric view of the clip of FIG. 1 with the body of a smart watch inserted; and,

FIG. 9 is an isometric view of the clip of FIG. 10 showing the body of the smart watch to be inserted.

The features shown in broken lines in the drawing depict environmental subject matter only, and form no part of the claimed design.
